UNITED STATES PATENT OFFICE.

GEORGE HENRY WHEARY, OF RACINE, WISCONSIN.

DESIGN FOR A TRUNK-FIXTURE.

45,318.

Specification for Design.

Patented Feb. 24, 1914.

Application filed September 29, 1913. Serial No. 792,521. Term of patent 14 years.

To all whom it may concern:

Be it known that I, GEORGE H. WHEARY, a citizen of the United States, residing at Racine, in the county of Racine and State of Wisconsin, have invented a new, original, and ornamental Design for Trunk-Fixture, of which the following is a description, reference being had to the accompanying drawing, forming part thereof.

Figure 1 is a plan view of a trunk fixture

showing my new design, and Fig. 2 is a central vertical sectional view thereof.

I claim:

The ornamental design for a trunk fixture, as shown.

GEORGE HENRY WHEARY.

Witnesses:

ANNA M. NELSON,
EMMA M. WOLFF.
